W. H. CLAYTON

TELEPHONE TRANSMITTER

Filed July 18, 1923

Inventor

W.H. Clayton,

By S. P. Wolhaupel Attorney

UNITED STATES PATENT OFFICE.

WILLIAM H. CLAYTON, OF PINE BLUFF, ARKANSAS.

TELEPHONE TRANSMITTER.

Application filed July 18, 1923. Serial No. 652,421.

To all whom it may concern:

Be it known that I, WILLIAM H. CLAYTON, citizen of the United States, residing at Pine Bluff, in the county of Jefferson and State 5 of Arkansas, have invented certain new and useful Improvements in Telephone Transmitters, of which the following is a specification.

This invention relates to a new and useful 10 improvement in telephone transmitters having primarily in view a novel construction and arrangement of instrumentalities producing a much more sensitive, and at the same time not so delicate an instrument as 15 those in common use.

To obtain the desired result, a principal 20 object of the invention is to provide a transmitter construction including electrodes associated with the diaphragm, and means 25 for effecting a great decrease in the amplitude of vibrations of the electrodes relative to the amplitude of vibrations of the diaphragm, thereby increasing the pressure, and diminishing the motion, imparted to the 30 contacting electrodes. It is proposed to obtain in that way a much more sensitive and reliable instrument and one that works through a much wider range, and because of the heavy increase of the pressure exerted by 35 the diaphragm a more substantial and reliable construction can be made, of almost any capacity for any desired purpose.

A further and distinctive object of the 40 present invention is to provide a transmitter in which the pressure on the contact points or electrodes is automatically maintained by the weight of the parts themselves, thereby eliminating all manual adjustments. At the same time this feature 45 of the invention permits an instrument to be made which is capable of being adjusted through a wide range, merely by varying the number, size and disposition of the parts.

A further object of the invention is to 50 provide a telephone transmitter of the character described which is extremely simple in construction, there being but few parts, and it is therefore cheap to manufacture. Also the invention aims to provide a sturdy 55 construction of instrument which is very sensitive and efficient.

With these and other objects in view

which will more readily appear as the nature of the invention is better understood the same consists in the novel construction, 55 combination and arrangement of parts, hereinafter more fully described, illustrated and claimed.

Referring to the accompanying drawing, 60 which shows one form of my invention, in which:—

Figure 1 is a vertical sectional view through the transmitter.

Figure 2 is a side elevation of the transmitter cover showing my invention applied 65 thereto, and

Figure 3 is a detail view showing a plurality of contacting electrodes.

Similar reference characters designate 70 corresponding parts throughout the several figures of the drawings.

Heretofore it has been generally held that sound vibrations are extremely minute and necessitate amplifying for more efficient use 75 in instruments of this character. My experiments have proven conclusively that instead of this fact being true, the magnitudes of the vibrations are already much too great and need a considerable reduction in order to produce the best results. By a 80 considerable reduction of the vibrations a much superior instrument is produced as it is free from most of the defects common to the transmitters now in commercial use.

In many other types of transmitters the 85 diaphragm is supported without the aid of any solid or rigid part at the rear but the working mechanism is usually directly back of the center, and the force of the vibrations is taken through the granulated carbon contacts directly against the solid back of the instrument, thereby suppressing some of the heavier vibrations, or, if due to improper adjustment, such heavier vibrations are not entirely suppressed the contacts will break 90 and cause clicking or rattling. Also, much the same effect is produced in these other types of transmitters by the tension put upon the parts to adjust them as well as by the weight of the parts themselves. To overcome and remedy these technical and practical defects in other types of telephone transmitters the present invention coordinates, in a novel way, the diaphragm, loosely

but firmly-contacting light electrodes, and a simple system of levers, operating to always hold the electrodes in contact and providing an increased leverage with resultant pressure to the contacting electrodes will be obtained, thus greatly reducing the amplitude of vibrations of the electrodes relative to the amplitude of vibrations of the diaphragm. This construction creates an instrument which is devoid of rattling and one which catches a great range of vibrations and carries the full heavy tones as well as the light thin tones. The reduction in the amplitude of vibrations of the contacting electrodes relative to the amplitude of vibrations of the diaphragm prevents the electrodes from breaking contact entirely and thereby prevents rattling to that extent, thus creating a very sensitive instrument which catches a great range of vibrations and carries the full heavy tones as well as the light thin tones.

In carrying out my invention, I provide a transmitter casing 5 which includes a cover 6 having the usual opening 7 therein for receiving the sound waves. Fixed to this cover is a pair of spaced posts 8 and 9 respectively. Secured to the rear face of the cover is a circular ring 10 concentrically arranged with respect to the opening 7 and formed with a recess 11 forming a seat having a diaphragm 12. It will be noted at this point that there is an absence of any solid or rigid part in rear of the diaphragm 12 and this assists to prevent the suppression or clicking of the heavier tones. Furthermore, the diaphragm is held in spaced relation by the seats 11 from the cover 6, thus forming an annular space which communicates with the outer air through the opening 7.

Secured to the post 9 is a stationary electrode 13 having a terminal 14 connected thereto.

To the rear side of the diaphragm and at its center is fastened a fixed contact 15 of a pyramidal or equivalent shape, and having its apex or crown contacting with the free end portion of a spring lever 16 having a fastening connection at its other end as at 16^a to the post 8 or other point of support. The vibrations which are transmitted to the lever 16 from the diaphragm 12 are transmitted from said lever to an electrode lever 18 by a pyramidal or equivalent shaped bearing block or point 17 which is fitted to the lever 16 in any suitable manner, at a point intermediate the ends of the said lever 16.

The electrode lever 18 is arranged to operate along side, and in approximal relation to, the lever 16, the free end of the lever 18 having a bearing engagement against the bearing block or point 17 of the lever 16, and opposite its free end portion the lever 18 is securely held or fastened as at 18^a in

the block or equivalent support 9, the intention of this construction being to give the lever 18 sufficient spring tension to firmly hold its contacting engagement with the bearing 17 and also to maintain the electrodes in proper relation and contact. The fastened ends of the lever 18 may continue to be bent to provide a binding terminal at 19 for a wiring connection.

An important function of the lever 18 is to carry, adjacent its fulcrum or fastened end, a carbon or equivalent electrode 20 which is made fast to said lever so as to move therewith and therefore constitutes a movable electrode. This movable electrode is arranged at one side of, and in spaced relation to, the stationary carbon or equivalent electrode 13. As shown, the stationary or fixed electrode 13 may be preferably formed with a beveled face 22 corresponding to the beveled face 23 of a relatively loose intermediate carbon or equivalent electrode 21 which is merely seated, of its own weight, in the approximately V-shaped groove or channel which is formed between the opposing faces of the stationary electrode 13 and the movable electrode 20. Therefore, it will be seen that the construction described in effect is the formation of a tapering channel or groove between the two electrodes 13 and 20 and to place in this channel or groove the V-shaped or equivalent shaped loose electrode 21 which under the force of gravity maintains its proper contacting relation with the two electrodes 13 and 20, and inasmuch as this group of electrodes constitutes the resistance it will be readily appreciated that the resistance will be diminished whenever the pressure of the movable electrode is increased in the direction of the stationary electrode. Furthermore, it will be understood that the particular construction described is merely typical of the invention because electrodes 13 and 20 may be of any desired and required length and according to the length of such electrodes 13 and 20 there may be any desired or required number of the loose intermediate electrodes 21 placed in the channel or groove between them, thus providing a wide range for the instrument according to the particular requirements that it is expected to meet.

From the foregoing it will be observed that the spring tension of the mounted ends of the levers 16 and 18 causes such levers to follow the vibrations of the diaphragm, but any permanent flexible connection would permit of the same result. And, in following the vibrations of the diaphragm the reduction in movement provided for by the lever 16 will be imparted to the operating or electrode lever 18 due to the relation of these two levers and the position of their fulcrums or mounted ends. Consequently the amplitude of vibrations of the movable

electrode 20 carried by the lever 18 will be considerably less than the amplitude of vibrations of the diaphragm 12.

This reduction in vibration of the movable electrode creates an instrument which is devoid of rattling and one which catches a great range of vibrations and carries the full heavy tones as well as the light thin tones. The ratio of this reduction I have found by actual practice should be not less than 4 to 1, that is 4 of the diaphragm to 1 of the movable electrode. I have definitely ascertained that the objections above noted begin to disappear when a ratio of 4 to 1 or 15 more is employed and that the best results I have been able to obtain thus far have been produced by a ratio of about 20 to 1.

Accordingly, the present invention provides a means of working any kind of a telephone transmitter with an increased leverage, that is to say, the present invention provides a telephone transmitter including in combination with its diaphragm, and an electric circuit variable by pressure suitable means, actuated by the diaphragm for transmitting the vibrations of the diaphragm to the variable electric circuit by a decreased motion and an increased pressure.

From the foregoing it is thought that the construction and advantages of the described improvement in telephone transmitters will be now apparent without further description, and it will be understood that various changes in the form, construction and minor details of construction may be resorted to without departing from the principle of operation or sacrificing any of the advantages of the invention.

I claim:

1. A telephone transmitter including in combination with the diaphragm and an electric circuit variable by pressure, means, actuated by the diaphragm, for transmitting the vibrations thereof to the variable electric circuit by decreased motion and increased pressure, at a ratio of not less than 4 to 1.

2. In a telephone transmitter, a diaphragm, a pair of motion reducing and pressure increasing levers arranged to be vibrated from the diaphragm, and electrodes included in the electrical circuit and subjected to pressure from one of said levers.

3. In a telephone transmitter, a diaphragm, a system of motion reducing and pressure increasing levers actuated by the diaphragm, and electrodes included in the electric circuit and subjected to pressure from the said system of levers.

4. In a telephone transmitter, a diaphragm, a system of motion reducing and pressure increasing levers actuated from the diaphragm, and a group of electrodes in-

cluded in the electrical circuit and subjected to pressure from said system of levers, said group of electrodes including an electrode carried by one of the levers, a stationary electrode spaced therefrom leaving an intervening channel, and a loose intermediate electrode seated in said channel.

5. In a telephone transmitter, the combination with a diaphragm, of relatively stationary and movable electrodes, and means actuated by the diaphragm for reducing the amplitude of vibrations of the movable electrode relative to the amplitude of vibrations of the diaphragm, at a ratio of not less than 4 to 1.

6. In a telephone transmitter, the combination with a diaphragm, of relatively stationary and movable electrodes, and means including levers actuated by the diaphragm for reducing the amplitude of vibrations of the movable electrode relative to the amplitude of vibrations of the diaphragm at a ratio of not less than 4 of the diaphragm to 1 of the movable electrode.

7. In a telephone transmitter, the combination with a diaphragm, of relatively stationary and movable electrodes, and means including levers actuated by the diaphragm for reducing the amplitude of vibrations of the movable electrode relative to the amplitude of vibrations of the diaphragm at a ratio of not less than 4 of the diaphragm to 1 of the movable electrode, one of said levers being directly actuated by the diaphragm and the other lever being actuated by the first mentioned lever to control the movements of the movable electrode.

8. In a telephone transmitter, the combination with a casing, of a diaphragm supported therein, relatively stationary and movable electrodes located in said casing, a main actuating lever fulcrumed at one end and having its free end cooperating with the diaphragm, and an operating lever for the movable electrode fulcrumed at one end and having its free end disposed in engagement with the actuating lever at a point adjacent the fulcrum thereof, said levers being related to provide for a decreased motion and increased pressure at a ratio of not less than 4 to 1.

9. In a telephone transmitter, the combination with a casing, of a diaphragm supported therein, relatively stationary and movable electrodes located in said casing, a main actuating lever fulcrumed at one end and having its free end cooperating with the center of the diaphragm, and an operating lever for the movable electrode fulcrumed at one end and having its free end disposed in engagement with the actuating lever at a point adjacent the fulcrum thereof, said movable electrode being mounted on the operating lever adjacent the fulcrum

thereof, said levers being related to provide for a decreased motion and increased pressure at a ratio of not less than 4 to 1.

10. In a telephone transmitter, the combination with a diaphragm, of relatively stationary and movable electrodes arranged in spaced relation forming a channel or groove therebetween, a loose electrode seated by gravity in said channel or groove, and 10 means actuated by the diaphragm for vary-

ing the amplitude of vibrations of the movable electrode relative to the amplitude of vibrations of the diaphragm.

In testimony whereof I hereunto affix my signature in the presence of two witnesses.

WILLIAM H. CLAYTON.
